DESIGN FOR AN AIRPLANE

Thomas P. Spence, Huntington, W. Va.

Application June 24, 1941, Serial No. 101,648

Term of patent 7 years

To all whom it may concern:

Be it known that I, Thomas P. Spence, a citizen of the United States, residing at Huntington, county of Cabell, and State of West Virginia, have invented a new, original, and ornamental Design for an Airplane, of which the following is a specification, reference being had to the accompanying drawings, forming a part thereof.

In the drawings:

Figure 1 is a top plan view of an airplane embodying my design,

Figure 2 is a side elevational view of the same, Figure 3 is a rear elevational view of the same on an enlarged scale, and

Figure 4 is a front elevational view of the same on an enlarged scale.

I claim:

The ornamental design for an airplane, as shown.

THOMAS P. SPENCE.
